CLAIM

The ornamental design for a bicycle headset cap with cover, as shown and described.

DESCRIPTION

FIG. 1 is a top perspective view of a bicycle headset cap with cover, showing my new design;

FIG. 2 is a bottom perspective view thereof;

FIG. 3 is a left side view thereof with the right, left, front and rear views being identical thereof;

FIG. 4 is a bottom view thereof; and,

FIG. 5 is a top view thereof.

The broken lines illustrate portions of the bicycle headset cap with cover that form no part of the claimed design.
